[57] **CLAIM**

The ornamental design for bed frame, as shown and described.

DESCRIPTION

FIG. 1 is a top perspective view of the bed frame of my invention;

FIG. 2 is a perspective view as seen from the front of the bed frame of my invention and illustrating the outer face of the foot board and the inner face of the head board;

FIG. 3 is a perspective view as seen from the rear of the bed frame of my invention and illustrating the outer face of the head board;

FIG. 4 is a perspective view as seen from the right of FIG. 1 and illustrating the outer face of the right side board, the inner face being plain throughout; and,

FIG. 5 is a perspective view as seen from the left of FIG. 1 and illustrating the outer face of the left side board, the inner face being plain throughout.

The inside of the footboard not shown is not part of the claimed design.
